UNITED STATES PATENT OFFICE.

MORIS RODOLITZ, OF BROOKLYN, NEW YORK.

DESIGN FOR A BODY FRAME FOR CHANDELIER.

Application filed October 3, 1925. Serial No. 15,015. Term of patent 3½ years.

To all whom it may concern:

Be it known that I, MORIS RODOLITZ, a citizen of the United States of America, residing at Brooklyn, New York, in the county of Kings and State of New York, have invented a new, original, and ornamental Design for a Body Frame for Chandeliers, of which the following is a specification, reference being had to the accompanying drawing, forming part thereof.

The drawing shows a perspective view of a body frame for chandeliers.

I claim:

The ornamental design for a body frame for chandeliers, substantially as shown.

MORIS RODOLITZ.
